M. A. Lawson

UNITED STATES PATENT OFFICE.

MARTIN A. LAWSON, OF MIDDLETOWN, OHIO.

WATER-TUBE BOILER.

Application filed August 4, 1922. Serial No. 579,644.

To all whom it may concern:

Be it known that I, MARTIN A. LAWSON, a citizen of the United States, residing at Middletown, in the county of Butler and State 5 of Ohio, have invented certain new and useful Improvements in a Water-Tube Boiler; and I do hereby declare the following to be a full, clear, and exact description of the invention, such as will enable others skilled 10 in the art to which it appertains to make and use the same.

This invention relates to a water tube boiler.

It is generally aimed to provide a more 15 efficient improved construction particularly adapted for automotive use and particularly in which maximum heating surface is afforded in comparison to its size and weight; in which all surfaces are stayed to resist internal and external strain and assure safety 20 from rupture or explosion; in which the unduly constant expansion and contraction caused by the water splashing over the hot surfaces as in vertical fire tube boilers is 25 minimized; in which maximum circulation of the water is assured and the parts are accessible for cleaning and repairing; in which the generation of steam will be exceedingly rapid; in which a very high rating in horse 30 power or pounds of evaporation is obtainable; in which hard or hot firing is afforded because of the efficient circulation; in which the firing may be accomplished by use of oil or gas as the fuel as the device is self-contained and internally fired; in which radiation 35 is kept to a minimum as the water jacket reduces the temperature and in which less danger is present of its becoming overheated due to all heating surfaces being surrounded by water; in which air leaks are 40 avoided as the fuel entrance is entirely enclosed whereby practically perfect combustion is assured and one in which the losses in the escaping gas or fuel are not as great as 45 in ordinary automotive boilers because the same on leaving the boiler contacts with the coolest tubes.

Additional objects and advantages will 50 become apparent from a consideration of the description following taken in connection with accompanying drawings illustrating one operative embodiment.

In said drawings—

Figure 1 is a view illustrating the invention 55 is substantially central longitudinal section;

Figure 2 is a cross sectional view through the entire boiler taken on the plane of line 2—2 of Figure 1; and

Figure 3 is a cross sectional view through 60 the entire boiler taken on the plane of line 3—3 of Figure 1.

Like reference characters designate like or similar parts in the different views. In reducing the invention to practice, a drum is 65 provided at 10, interiorly screw threaded at its ends as at 11 engaged by screw threads of end heads 12. A water inlet for the drum 10 is provided at 13 and an outlet or drain at 13^a. An inner drum 14 is disposed within the drum 10 and spaced therefrom at its end and periphery to form a water space 15. Horizontally disposed water tubes 16 are provided within the drum 14 and are connected to the tube sheets 17 which close the 75 ends of drum 14 and are screwed thereto as at 18. Thus any approved method of connecting the tubes 16 to the sheets 17 may be resorted to but the tubes are preferably passed through openings in the sheets, ex- 80 tended through said openings and welded to the sheets. Axially of the drum 14, a tube 19 larger than the tubes 16 is secured to the tube sheet 17 in the same manner as the tubes 16. Disposed through the tube 19 is a 85 tie rod 20 which is detachable therefrom and which also passes detachably through the heads 12 and exteriorly of the same is screw threaded and receives nuts as at 21 thereon.

Snugly screw threaded in openings 22 and 90 23 in the drums 10 and 14, respectively, are screws 24. These screws serve to assist the tie rod 20 in positioning and fastening the drum 14 in place and are capable of separate adjustment to efficiently hold the drum 95 14 in place.

The interior of the drum 14 forms the heating chamber and the water is adapted to circulate in the pipes 16 as will be understood. The gas or fuel inlet is provided as 100 at 26 and may consist of a nipple 27 generally of cylindrical form expanded in an appropriate opening of the drums 10 and 14 and welded thereto. The fire opening for the drum 14 is shown at 28 and may consist of a nipple 29 expanded in appropriate openings of the drums 10 and 14 and welded to them. Within the drum 14 a suitable baffle wall 30 is provided which terminates short of the upper extremity of drum 14 as shown 110 and the tubes 16 and 19 extend therethrough. Disposed above the drum 10 in offset re-

lation is a live steam cylinder 31. This cylinder may consist of a drum 32 and rest on blocks 33 interposed between the same and the top of drum 10. A clamp band 34 is 5 adapted to surround the drum 10 adjacent each end and have its terminals 35 overlap the ends of the block 33. Clamp bands 36, smaller than band 34 surround the drum 32 and have their terminals 37 overlapping the 10 terminals 35 and in the blocks 33. Detachable bolts 38 may be passed through the blocks 33 and terminals 35 and 37 to form an efficient support and mounting for the drum 32. At its ends, drum 32 is interiorly 15 screw threaded as at 39 for engagement by the screw threads of end heads or closures 40. A detachable tie rod 41 extends axially of the drum 42 and removably through heads 40, being screw threaded exteriorly 20 thereof and having securing nuts 42 applied thereto. Suitable conduits in the form of elbows 43 extend from drum 10 to the heads 40, preferably being detachably connected to said parts in any suitable manner so as 25 to establish communication between the interior of drum 10, that is the water space and the interior of drum 32. Live steam from drum 32 may be led therefrom through an outlet opening or nipple 44.

30 It will thus be seen that the water supplied to the drum 10 through the inlet 13 circulates in the drum and through the pipes 16, being efficiently heated by the fire in the drum 14, generating steam which travels 35 from the water space or drum 10 through the conduits 43 into the live steam cylinder or chest 31 and from the same passes to the source of use through the outlet 44.

40 All parts used are of course of suitable metal, the heads 12 and 40 preferably being of sheet steel, the two sheets 17 being of

sheet steel and the drums 10, 14 and 31 being of cold drawn seamless steel tubing.

As merely one example of the practice of the invention has been given, it is to be 45 understood that changes may be resorted to within the spirit and scope.

I claim as my invention:—

A boiler having a water drum, end heads 50 detachably secured to said water drum, a heater drum within said water drum, a tie rod carried by the heater drum and having its terminals extending through openings in said end heads, detachable fastenings on 55 said terminals exteriorly of the drums and engaging said end heads to supplement the fastening of the end heads to the first drum, nipples connected to the drums and engaging opposite ends thereof to constitute 60 inlet and exhaust openings respectively for the products of combustion, a live steam cylinder offset from the water drum, removable end heads for the live steam cylinder having threaded connection to the live steam cylinder, a tie rod extending longitudinally 65 of the live steam cylinder and through its end head, fastenings on the terminals of the latter tie rod engaging the latter end heads, 70 connections extending from the latter end heads to the water drum, blocks resting on the water drum inwardly of said connections, the live steam cylinder resting on said blocks, clamps surrounding the water drum, clamps surrounding the live steam cylinder, 75 said clamps having their terminals in overlapping relation and disposed at the sides of the blocks, and fastenings passing through the terminals of the clamps and said block to secure the clamps and the blocks in place.

In testimony whereof I affix my signature.

MARTIN A. LAWSON.
